UNITED STATES PATENT OFFICE.

SAMUEL PRIOR, OF TRENTON, NEW JERSEY.

HEEL FOR BOOTS OR SHOES.

SPECIFICATION forming part of Letters Patent No. 276,279, dated April 24, 1883.

Application filed February 2, 1883. (No model.)

To all whom it may concern:

Be it known that I, SAMUEL PRIOR, a citizen of the United States, residing at Trenton, in the county of Mercer and State of New Jersey, 5 have invented certain new and useful Improvements in Heels for Boots and Shoes, and in the art or process of making the same, of which the following is a specification.

Heretofore heels for boots and shoes have 10 been made of leather, being built up by successive lifts, or of metal or composition cast in one solid piece. The leather heels thus built up are expensive in both labor and material, while the metal or composition heels are 15 objectionable, as they do not present the appearance of leather. By my method I am enabled to form a complete heel at less expense than by the old method of building up by successive lifts, and such heel has the appearance and 20 elegance of a solid leather heel, and is as durable. I also secure the additional advantage of shaping the heel in the operation of making it, thus dispensing with waste of material and avoiding the labor of shaping the heel after it 25 is built up.

Figure 1 shows my heel. It is the same in shape and outward appearance as the ordinary leather heel. Fig. 2 shows a heel cut in section.

In Fig. 2, A is the outer surface of the heel, 30 and B is the inner filling. The heel is composed of this outer surface or covering of leather, filled with leather-scrap and cement, or any suitable material, pressed into shape in a die or mold of the requisite size and shape.

35 To make one of these heels, I first provide

a mold or die of the proper form. Within this I place a piece of leather of such size and shape that it will line the bottom and sides of the die. I then fill in the space within such lining with leather-scrap and cement, or any suitable 40 material. Over this I then fold down the upper portions of the piece of leather which lines the die; or, if those upper portions are scant, I lay over such filling another piece of leather of the contour of the heel. I then apply a 45 heavy pressure to the mold or die thus charged, and the whole is compacted into one solid mass. On releasing it from the mold or die the piece first placed in the mold will be found to have taken the exact shape of the mold, and the composition fully fills it, thus making a 50 heel, as shown at Fig. 2, composed of an outer skin, A, of leather, with an interior filling, B, of any suitable material. The same operation also shapes the heel ready for use.

What I claim as my invention, and desire to 55 secure by Letters Patent, is—

That art or process of forming a boot or shoe heel which consists in lining a die or mold of the proper form with a piece of leather, placing within the leather a filling of leather-scrap 60 and cement, or any suitable material, and then subjecting the same to pressure, thereby shaping and compacting the same, substantially as described.

SAMUEL PRIOR.
